(Cl. D58—8)

FIG. 3.

Fig. 1 is a side elevational view of a carafe embodying our new design;

Fig. 2 is a plan view of Fig. 1; and

Fig. 3 is a cross section on line 3—3 of Fig. 1.

The side not shown is the same as the side shown.

The characteristic features of our design for the carafe disclosed reside in the area above the plain lower side walls thereof.

We claim:

The ornamental design for a carafe, substantially as shown and described.
